UNITED STATES PATENT OFFICE.

JOHN WOOL GRISWOLD, OF TROY, NEW YORK.

BARBED-WIRE FENCE.

SPECIFICATION forming part of Letters Patent No. 465,641, dated December 22, 1891.

Application filed June 15, 1891. Serial No. 396,257. (No model.)

To all whom it may concern:

Be it known that I, JOHN WOOL GRISWOLD, of Troy, Rensselaer county, New York, have invented a new and useful Improvement in 5 Barbed-Wire Fences, of which the following is a specification.

My invention relates to that class of wire fencing which is composed of a series of links, usually barbed; and it consists in the construction of said links and their combination to form a continuous fencing.

In the accompanying drawings, Figure 1 is a plan view of my improved fencing. Fig. 2 is a side view, and Fig. 3 is a sectional view 15 on the line 3 3 of Fig. 2.

Similar letters of reference indicate like parts.

Each link *a b* consists of a length of wire *A*, doubled or halved on itself to form at one end 20 of said link the eye *B*. One end of the doubled-over wire *A* is bent to form an eye *C*. The other end of said doubled-over wire *A* is bent in the opposite direction to form an eye *D*. The two eyes *C* and *D* are placed side by side, 25 as shown. The extremities *E F* of the wire *A* cross between the parts of said wire and are sharpened and protrude therefrom, as shown in Figs. 2 and 3, to form barbs.

In uniting the links to form the fencing the eye *B* of one link, as *b*, engages with the parallel eyes *C D* of the adjacent link *a*. 30

This fencing is strong, durable, and easily and cheaply made.

I claim—

1. A wire-fencing link composed of a length 35 of wire doubled to form a loop or eye *B* at one extremity of the link and having its ends bent over in relatively opposite directions to produce the eyes *C D*, the extremities *E F* of said wire being crossed between the parts thereof 40 and protruding to form barbs.

2. A wire fencing composed of a series of 45 enchain links, each link being composed of a length of wire doubled to form a loop or eye *B* at one extremity and having its ends bent over in relatively opposite directions to produce the eyes *C D*, the extremities *E F* of said wire being crossed between the parts thereof and protruding to form barbs, and the eyes *C D* of one link engaging with the eye *B* of 50 the next adjacent link.

JOHN WOOL GRISWOLD.
